US0D1013505S

(12) **United States Design Patent** (10) Patent No.: **US D1,013,505 S**
(45) Date of Patent: ** Feb. 6, 2024

(54) **PACKAGING FOR FOODSTUFFS**

(71) Applicant: **Jelly Drops Limited**, London (GB)
(72) Inventor: **Claudia Arnold**, London (GB)
(73) Assignee: **Jelly Drops Limited**, London (GB)
(**) Term: **15 Years**
(21) Appl. No.: **35/513,608**
(22) Filed: **Dec. 24, 2021**

(80) **Hague Agreement Data**

Int. Filing Date: **Dec. 24, 2021**
Int. Reg. No.: **DM/218697**
Int. Reg. Date: **Dec. 24, 2021**
Int. Reg. Pub. Date: **Feb. 11, 2022**
